UNITED STATES PATENT OFFICE

ROBERT H. SHARP, OF MARENGO, ILLINOIS, ASSIGNOR TO MCGILL METAL PRODUCTS COMPANY, OF CHICAGO, ILLINOIS, A CORPORATION OF ILLINOIS

PORTABLE CHANGE MAKER

Application filed January 13, 1926. Serial No. 80,884.

The invention relates to a portable change maker, and particularly to an improved type of change maker and carrier adapted to be worn by any person who receives coins and is required to make change.

The change maker of the invention is especially useful for street car conductors and others who are required to make change very rapidly and accurately for their patrons.

10 The invention is also useful in connection with portable change makers to provide means whereby the number of coins or tokens to be ejected by one operation may be altered as to one or all coin containing tubes immediately upon changes or alterations of ordinances relative to street car fares, or changes or alterations in the street car companies' rules and regulations regarding street car fares, or at the desire or wish of 20 the user.

One of the objects of the invention is to provide a structure whereby the person operating the change maker may, by pressing a trigger or lever, eject into his hand a predetermined number of coins or tokens from any of the tubes or receptacles containing the coins or tokens, which tubes may be suitably joined together to make up the portable change maker.

30 Another object of the invention is to construct the coin supporting mechanism in each of the coin tubes so that an adjustment may readily be made which will cause a greater or less number of coins to be ejected into the 35 hand of the operator.

A further object of the invention is to supply the coin support or bottom with a number of units or plates which may be secured together either above or below the main base 40 portion of the change maker for each coin containing tube to enable the operator to eject the required coin or coins.

Another object of the invention is to construct the coin support or bottom underlying 45 each of the coin tubes with means whereby any combination or arrangement of the coin support or bottom plates may be made, and whereby any desired or predetermined number of coins may be ejected from the coin 50 tubes by one operation.

An additional object of the invention is to provide a support or bottom for the coins in stacked arrangement in the coin tube, which, while being adjustable and removable, shall be accurately placed and firmly held so that 55 the change maker in its operation and performance, shall be positive, definite, and reliable in every way.

It is also an object of the invention to construct the main base portion of the change 60 maker underlying the coin tubes with recess and slot means whereby the stack of support or bottom units or plates may be placed in substantially exact registry, and whereby any combination or arrangement of the units or plates may be made without complete disjunction of the stack of units or any of the units composing the stack.

A further object of the invention is to provide the change maker with ejecting rings 70 which are of a uniform design, and in also making the support or bottom plates of one uniform design, thus avoiding the difficulty and expense involved in the manufacture and assembly of the change maker, because all of these parts have uniformity of design, and, therefore, are more readily assembled for use.

The invention will be explained and more readily understood when read in conjunction with the accompanying drawings, which illustrate embodiments of which the invention is susceptible, it being obvious that changes and modifications in the structure may be made without departing from the spirit of the invention, as expressed in the appended claims forming a part hereof.

In the drawings:

Figure 1 is a front elevational view of a portable change maker embodying the invention, and showing the support or bottom plates beneath the coin tubes in assembled relation, and also showing them stacked in operative position with various numbers of plates.

Figure 2 is a cross sectional view of the 95 portable change maker on the line 2-2 of Figure 1, looking in the direction of the arrows.

Figure 3 is a vertical view through the portable change maker and one of the operat-

ing levers thereof, showing one of the coin tubes in side elevation, and is on line 3—3 of Figure 2, looking in the direction of the arrows.

5 Figure 4 is a top plan view on line 4—4 of Figure 1, showing the coin ejector ring, the segmental gears which operate to move the ejector ring, and a top plan view of one of the support or bottom plates.

10 Figure 5 is a view similar to the one shown in Figure 4, except that the ejector ring is shown in its outermost position at the moment the coin is ejected.

15 Figure 6 is an enlarged view of the bottom portion of one of the coin tubes, of the ejector ring, and the stack of support or bottom plates, the view being on line 6—6 of Figure 2, looking in the direction of the arrows.

20 Figure 7 is a bottom plan view of a portion 20 of the main base plate of the portable change maker on the line 7—7 of Figure 6, looking in the direction of the arrows.

25 Figure 8 is a perspective view on an enlarged scale, of one of the support or bottom plates used in the change maker.

30 Figure 9 is an enlarged cross sectional view of a modified form of main base plate, and showing the lower portion of the coin tubes and ejector ring, similar to those shown in Figure 6.

35 Figure 10 is a bottom plan view of the modified form of main base plate with a separable slotted guide member for the stack of support or bottom plates taken on line 10—10 of Figure 9, looking in the direction of the arrows.

40 Figure 11 is an enlarged view of the separable slotted guide member of Figures 9 and 10.

45 Figure 12 is a lower plan view of the ejector ring showing the segmental gear integral therewith, an integral tab, and an associated reinforcement on both sides of the tab.

50 Figure 13 is a view, partly in section, on the line 13—13 of Figure 4, looking in the direction of the arrows, and

55 Figure 14 is a plan view looking upwardly at the bottom face of a portion of the auxiliary base plate.

60 The portable change maker as shown in the drawings comprises a plurality of tubes or receptacles adapted to contain coins or tokens. Five tubes or receptacles are shown, but it will be understood that any number of tubes or receptacles may be used with the invention.

65 As shown, the first coin tube 15 is adapted to contain quarters; the next tube 16, is adapted to contain dimes; the next two tubes, 17 and 18, are adapted to contain nickels and pennies, respectively, and the last tube 19 is adapted to contain tokens, which are used in considerable numbers throughout the country. The coin tubes are each provided with openings 20, which are placed in staggered relation to enable the operator to see how many coins or

tokens he has in each coin tube, and to permit him to arrange them in proper stacked relation, should the coins not be in order within the tubes.

70 A single unitary cover plate 21 is secured in place across the tops of each of the tubular coin receptacles. This integral top plate is suitably formed with coin slots 22, through which the coins of various denominations, and the tokens may be deposited by the operator in their respective tubular compartments. Rods or posts 23 and 24 are secured in the top plate 21 and the main base plate 25 passing through the auxiliary base plate and tube holder 26. The unitary top plate 21 is provided with an extension arm 27 through which the rod or post 24 extends, for the purpose of adding another tubular coin receptacle to the bank of receptacles, if that should be necessary or desirable. Side hooks which are slidably connected to the rods or posts 23 and 24, but which are not shown, are used to suspend the portable change maker on the operator by means of suitable holding straps. The main base plate 25 extends from end to end of the change maker. It is suitably secured to the rear vertical curved plate 28, which latter plate extends forwardly at the sides of the change maker at 29 and 30. The rear curved wall or plate 28 is provided with an inwardly extending upper flange 31, best shown in Figure 3 of the drawings. The main base plate 25, the rear curved plate 28, the extensions 29 and 30, and the flange 31 may be integral, and formed in any suitable manner, or they may be made of separate pieces of metal suitably secured together.

75 80 85 90 95 100 105 110 115 120 125 130

The auxiliary base plate and tube holder 26, which is preferably a die casting, suitably made to carry out its various purposes, is secured in a suitable manner above the main base plate 25. This die casting 26 provides the seat for the lower ends of the tubular coin receptacles, 15, 16, 17, 18 and 19. It is formed with relatively large cut-out openings 32 at its front. Coin ejector rings 33, 34, 35, 36 and 37 swing outwardly from above the cut-out openings 32. Each of the coin ejector rings has a portion cut out at its rear at 38 to permit the ring to eject a coin or coins, and allow the ring, because of the opening 38, to swing outwardly beyond the stack of support or bottom plates 39, 40, 41, 42 and 43. The auxiliary base plate casting 26 is also provided with small cut-out openings 44 back of the openings 32, through which the tongue or extension 45 of the coin ejector rings may swing when the coin ejector rings are moved either forward or backward.

130

The coin ejector rings 33, 34, 35, 36 and 37 respectively, are of varying heights and different diameters, according to the size of the coins or tokens they are designed to eject. The coin ejector rings are normally in regis-

try with and placed beneath the tubular coin receptacles, so that coins or tokens deposited therein fall to the bottom thereof with the lowermost coin or token resting or seating upon the topmost plate 39 of the stack of supporting plates secured at the bottom of each of the tubular coin receptacles, and which plates will be more particularly described hereinafter. Detail views of one of the coin ejector rings are shown in Figures 4, 5 and 12. As illustrated, the coin ejector ring is provided with the integral tongue or extension 45 having lateral reinforcing portions 46 and 47, and an integral arm or extension 48 pivotally held on the pivot post 49 integral with the auxiliary base plate 26 and extending downwardly therefrom. The pivot post 49 extends into an aperture in the main base plate 25, and the arm or extension 48 pivots intermediate the main and auxiliary base plates, 25 and 26, respectively, in a recess 26a formed in the under side of said auxiliary base plate. On the outer edge of the arm or extension 48 a gear segment 50, having teeth 51, is provided. The gear segment 50, with its teeth 51, and the arm or extension 48, are integral with the coin ejector ring, such as 33.

It will be understood that each of the coin ejector rings, except for its height and diameter, and the associated ejecting mechanism, including the gear segments, operating levers and mechanism associated with each of the tubular coin receptacles, are identical. It will thus be seen that because of the uniformity of the mechanism and associated parts in connection with each coin tube, the expense of manufacturing differently designed coin ejector rings and other apparatus to accomplish the result secured by this invention, is avoided, and also the expense and attendant difficulties in connection with the assembly of such mechanism and parts.

A gear segment 52, provided with an aperture 53, and having its teeth 54 in mesh with the teeth 51 of the gear segment 50 of the coin ejector ring, such as 33, is pivotally mounted on the pivot post 55 to the rear of the pivot post 49. The pivot post 55 is also integral with the auxiliary base plate 26 and extends downwardly therefrom. The pivot post 55 also extends into an aperture in the main base plate 25 and the gear segment 52 also pivots intermediate the main and auxiliary base plates 25 and 26, respectively, in the recess 26a formed in the under side of said auxiliary base plate.

A trigger or lever 56 is provided for each of the coin ejector rings. The trigger or lever 56 is for the purpose of swinging the coin ejector ring outwardly to a position as shown in Figure 5, whereby the coin ejector ring is moved over a semi-circular cut-away opening 57 in the main base plate 25. The trigger or lever 56 is pivotally mounted on

inwardly turned tongues or lugs 58 struck from the curved rear wall 28. The trigger or lever 56 is provided with a downwardly extending integral finger or arm 59, having a reduced end 60, as best shown in Figure 3 of the drawings. The reduced end 60 of the arm 59 engages in the aperture 53 of the gear segment 52, and has the reduced end 60 thereof positioned to slidably engage in the guide slot 61 provided for the purpose in the base plate 25, and a registering slot 61a in the auxiliary base plate 26 above the guide slot 61. When the trigger or lever 56 is depressed the finger or arm 59 swings inwardly or rearwardly, and its reduced end 60, being engaged in the aperture 53 of the gear segment 52, and disposed normally at the forward end of the slot 61 of the base plate 25, pivotally swings or rotates the gear segment 52, the teeth 54 of which being in mesh with the teeth 51 of the gear segment 50 of the coin ejecting ring, such as 33, swings the coin ejector ring outwardly from the frame of the portable change maker from beneath the tubular coin receptacle into register with the semi-circular cut-away portion 57 of the base plate 25 to permit a coin or coins carried outwardly by the coin ejector ring, to be ejected from the top curved coin support plate 39 and to fall therefrom into the hand of the operator.

The trigger or lever 56 is provided with a coil spring 62 coiled around the pintle 63 with an end of the spring bearing against the rear wall 28, and the other end engaged behind the finger or arm 59 of the trigger or lever, so that depressing movements of the trigger or lever are resisted by the spring, and after the depression of the trigger or lever, it is returned by said spring 62 to normal position, and the coin ejector ring, such as 33, is also returned by the spring 62 to its normal position.

The plurality of relatively small curved plates 39, 40, 41, 42 and 43, which are of a thickness corresponding to the thickness of the coins or tokens in the particular tubular coin receptacle in which they are to be used, are arranged in stacked relation beneath each of the tubular coin receptacles 15, 16, 17, 18 and 19, and form the support or bottom upon which the stack of coins in the coin tube normally rests. These stacks of relatively small curved plates 39, 40, 41, 42 and 43 are adjustably and removably held to the main base plate 25 by means of the screw bolts 64 and 65, the screw threads of which are at the ends thereof only. Each of the plates 39, 40, 41, 42 and 43 is provided with a pair of holes 66 and 67 for the reception of the screw bolts 64 and 65. The holes 66 and 67 in the end plate 39 are screw-threaded for the reception of the screw-threaded ends of the screw bolts 64 and 65. The holes 66 and 67 in the other plates are plain, but are larger

in diameter to allow plenty of play room for the screw bolts 64 and 65, as more particularly shown in Figures 6 and 9.

In the preferred embodiment of the invention the base plate 25 is formed with the curved recess or depression 68. The recess or depression is formed with a contour substantially similar to the plates 39, 40, 41, 42 and 43, and permits the stack of plates to be readily placed in position. A curved guide slot 69 is provided in the central part of the recess 68 to accommodate the screw bolts 64 and 65 which hold the relatively small curved plates 39, 40, 41, 42 and 43 in position on the ledges 70 and 71 in the recess 68 in the base plate 25. It will be obvious that with this arrangement the operator may secure as many of these relatively small curved plates 39, 40, 41, 42 and 43 above the base plate 25 as he desires. Inasmuch, however, as a full quota of five of these plates is normally supplied for each of the tubular coin receptacles, the operator will store the remainder of the five plates which he does not use, by fastening them into position beneath the recess 68 in the base plate 25. Whenever the operator desires to add to the number of plates of the stack above the base plate 25, he loosens the screw bolts 64 and 65, places the desired number of curved plates in position above the recess 68 in the base plate 25, fastens the screw bolts 64 and 65, and the particular tubular receptacle is then ready for use.

It will thus be seen that whenever it is desired to make a change as to the relatively small curved plates 39, 40, 41, 42 and 43 as to having one or more of the plates above the main base plate 25, the two screw bolts 64 and 65 may be loosened slightly in the screw-threaded holes 66 and 67 in the end plate 39, and all of the plates, together with the two screw bolts, may be slid as a unit from their position on the ledges 70 and 71 in the recess 68 of the main base plate 25 outwardly through the coin ejector ring, such as 33, and may be dropped into the hand of the operator, the coin ejector ring 33 having been extended by means of the trigger or lever 56, to its outermost position. The entire stack of plates, and the two screw bolts as a unit, may readily be returned to position on the ledges 70 and 71 in the curved guide slot 69 by loosening the stack of plates on the screw bolts 64 and 65, without however, permitting the end plate 39 to be entirely free from the ends of the screw bolts 64 and 65, thereby leaving plenty of room between each two plates, and permitting the entire stack, as a unit, to be slid into place in the recess 68 with the ledges 70 and 71 at the sides of the curved guide slot 69 sliding between any two of the said plates, or sliding between the lowermost of said plates 43, and the heads of the screw bolts 64 and 65. If the ledges 70 and 71 slide between the plates 39 and 40, the uppermost plate 39

will fill the recess 68 so that the upper face of the base plate 25 will be level. When all of the plates 39, 40, 41, 42 and 43 are below the ledges 70 and 71, or when plate 39 at the ends of the screw bolts 64 and 65 fill the recess, the maximum number of coins which the coin ejector ring is capable of ejecting, are ejected. When an additional plate, such as 40, is also placed above the ledges 70 and 71, one coin less may be ejected from the bottom of the stack of coins by the coin ejector ring. When two additional plates, such as 40 and 41, have been added to the stack above the recess ledges 70 and 71, two coins less may be ejected by the coin ejector ring, and when three additional plates, such as 40, 41 and 42, have been placed in position above the ledges 70 and 71, three coins less may be ejected from the bottom of the coin stack by the coin ejector ring, and so on as to the fourth and additional plates. In each case the unused small curved plates of each stack are stored below the main base plate 25.

In Figure 6 there is shown a stack of five plates, 39, 40, 41, 42 and 43, two of the plates 39 and 40 being above the base plate 25, and three of the plates 41, 42 and 43 being below the base plate 25. This would permit of the normal ejection of four coins from the bottom of the stack of coins in the tubular coin receptacle.

In Figure 1 of the drawings one plate 43 is shown below the base plate 25 in connection with the tubular coin receptacle 16; two plates 42 and 43 are shown below the base plate 25 in connection with the tubular coin receptacle 17; three plates 41, 42 and 43 are shown in connection with the tubular coin receptacle 15, and four plates 40, 41, 42 and 43 are shown below the base plate 25 in connection with the tubular coin receptacle 19. As to the tubular coin receptacle 18, no base plates are shown. In this case they are all above the main base plate 25.

The integral tongue or extension 45, with the lateral reinforcement webs 46 and 47, and the immediately adjacent portions of the coin ejector ring, such as 33, are for the purpose of supporting the remaining coins or tokens of the stack in the tubular coin receptacle when the coin ejector ring, such as 33, is at its outermost position at the moment when the ejected coins or tokens drop into the operator's hand. The reinforcement webs 46 and 47 strengthen the tongue or extension 45, which has considerable strain upon it. If the integral tongue or extension 45 were not present, the coins or tokens remaining in the tubular coin receptacle after the ejection of the lowermost coins or tokens, would become tilted in the tube, and cause difficulty, and prevent the return of the coin ejector ring, such as 33, upon release of the trigger or lever 56.

It will be understood that the auxiliary

base plate or die casting 26 may be formed for use in connection with a single tubular coin receptacle, or it may be formed for use in connection with a bank of tubular coin receptacles. The details of construction of the auxiliary base plate 26 for use in connection with a bank of tubular coin receptacles would be identical for use in connection with each particular tube except as the casting would have to be made to fit the different sized tubular receptacles for the coins of various denominations.

A modified form of the main base plate and curved slotted guide plate attached thereto is shown in Figures 9, 10 and 11. The main base plate 72 is provided with an aperture 73. This aperture is curved and conforms in outline to each of the relatively small curved support or bottom plates 74, 75, 76, 77 and 78. A separate guide plate 79, provided with a curved slot 80, is secured to the bottom face of the main base plate 72 by means of the screws 81 and 82, passing through the holes 83 and 84 of the slotted guide plate 79, and into the main base plate 72. The slotted guide plate 79 is secured in place directly beneath the aperture 73 in the main base plate 72. By this construction a recess 85 is formed in the main base plate 72, and ledges 86 and 87 are provided, upon which the relatively small curved support or bottom plates 74, 75, 76, 77 and 78 may slide and be seated. The procedure to be followed in connection with the modified structure shown in Figures 9, 10 and 11, and the results obtained thereby, are substantially identical with the procedure and the results secured by the construction shown in the other figures of the drawings, showing the main base plate 25 with the recess 68 and associated construction.

The mode of operation of the portable change maker is as follows:

The operator drops the various coins and tokens received according to their denominations in the proper tubular coin receptacles 15, 16, 17, 18 and 19. As the coins fall in the tubes they are stacked therein, the lowermost coin in each tube seating or resting upon the uppermost plate 39 within the coin ejector ring, such as 33. When the operator wishes to obtain a coin, or a certain number of coins of a certain denomination, he depresses the trigger or lever 56 associated with the particular tubular coin receptacle. The depression of the lever 56 causes the backward movement of the reduced end 60, which, in turn, causes the rotation of the segmental gear 52, the teeth 54 of which are in mesh with the teeth 51 of the gear segment 50 integral with the coin ejector ring of the particular tubular receptacle. This movement of the gearing causes the coin ejector ring to swing outwardly into position to register over the semi-circular cut-

away portion 57 of the main base plate 25, which permits the coin or coins carried in the particular coin ejecting ring, and resting on the stack of plates 39, 40, 41, 42 and 43 to be ejected therefrom and to fall by gravity through the ring into the hand of the operator. At the moment the coin ejector ring is at its outermost position, the tongue or extension 45, with the reinforcement web portions 46 and 47, and the immediately adjacent portions of the coin ejector ring, have been swung to a position substantially in the center of the tubular coin receptacle underneath the bottom of the stack of coins which are to remain in the tube.

Upon release of the trigger or lever 56, the coin ejector ring, such as 33, is caused to be returned to its normal position beneath the tubular coin receptacle, and is kept in position against the auxiliary base plate 26 because of action of the coil spring 62.

The mode of operation regarding the small curved support or bottom plates has been sufficiently described above, and will not need to be repeated.

Having thus described my invention, what I claim and desire to secure by Letters Patent is:

1. In a change maker of the class described, a coin tube, coin ejecting mechanism, a base plate below said coin tube, an aperture in said base plate beneath said coin tube, a plurality of coin-supporting plates, one or more, as desired of said coin-supporting plates being adapted to be secured above said base plate to enable a variable number of coins to be ejected from said coin tube.

2. In a change maker of the class described, a coin tube, coin ejecting mechanism, a main base plate below said coin tube, a curved slot in said main base plate, a coin-supporting plate, and means in said curved slot whereby said coin-supporting plate may be held either above said main base plate or below said main base plate, said means adapted to slide in said curved slot.

3. A change maker of the class described comprising a coin tube, coin ejecting mechanism, a main base plate beneath said coin tube, and a coin support composed of a stack of plates, the plates of the support being adapted to be placed either above or below said main base plate.

4. A change maker of the class described comprising a coin tube, coin ejecting mechanism, a main base plate beneath said coin tube, said base plate being provided with a curved slot, and a coin support composed of a stack of plates, the plates of the support being adapted to be placed either above or below said main base plate, said stack of plates being adapted to slide through the medium of said slot.

5. A change maker of the class described

comprising a coin tube, coin ejector mechanism, a main base plate beneath said coin tube, and a coin support composed of a stack of plates, the plates of the support being 5 adapted to be placed either above or below said main base plate, means adjustably securing said plates, said stack of plates being arranged with relation to said securing means whereby any of the plates of said stack may 10 slide upon said main base plate.

6. In a change maker of the class described, a coin tube, ejecting mechanism, a slotted base plate, and means beneath said coin tube providing a support whereon a coin may rest 15 before being ejected by said ejecting mechanism, said means comprising the support being adjustable and permitting variation in the height of said support with relation to the bottom of said coin tube to enable a pre- 20 determined number of coins to be ejected from beneath said coin tube, said support being slidable through the medium of said slotted base plate.

7. A change maker of the class described, 25 comprising a coin tube, a main base plate beneath said coin tube, said base plate being provided with a curved slot, a coin support directly beneath said coin tube composed of a plurality of relatively small curved plates, 30 said plurality of relatively small curved plates being adapted to slide through the medium of said slot.

8. A change maker of the class described, comprising a coin tube, coin ejector mechanism, a main base plate beneath said coin tube, said base plate being provided with a curved slot, and a curved cut-out portion, a coin support directly beneath said coin tube composed of a plurality of relatively small 35 curved plates, said plurality of relatively small curved plates being adapted to slide through the medium of said slot, and each having an end curved to register with the curved cut-out portion of the main base plate 40 below said coin tube.

45 9. In a change maker of the class described, a coin tube, coin ejecting mechanism, a main base plate below said coin tube, said main base plate being provided with a curved recess portion directly beneath said coin tube, a curved slot within said recess portion, a plurality of coin supporting plates slidable through the medium of said slot within said recess, being adjustable and removable 50 through the medium of said slot, said plurality of plates being secured together by means of a bolt screw-threaded at one end passing through each of said plates, said bolt being longer by the amount of thickness of said main base plate than the combined thickness of said plates.

55 10. In a change maker of the class described, a coin tube, coin ejecting mechanism, a main base plate below said coin tube, said main base plate being provided with a curved

recess portion directly beneath said coin tube, a curved slot within said recess portion, a plurality of coin supporting plates slidable through the medium of said slot within said recess, being adjustable and removable 60 through the medium of said slot, said plurality of plates being secured together by means of a bolt screw-threaded at one end passing through each of said plates, which bolt is of sufficient length to permit a plurality of coin supporting plates to be placed above said main base plate, and a plurality of coin supporting plates to be placed below said main base plate, said bolt being longer by the amount of thickness of said main base plate than the combined thickness of said plates, the uppermost one of said plurality of coin supporting plates having a screw-threaded opening for the reception of said bolt, the remaining coin supporting plates 65 having holes for the reception of said bolt, which are not provided with screw threads.

70 11. In a change maker of the class described, a coin tube, an auxiliary base plate casting adapted to receive the lower end of said coin tube, ejecting mechanism comprising a pivoted coin ejector ring, a trigger adapted to operate said ejecting mechanism, a main base plate, means provided beneath said coin tube to support coins before the same are ejected by said ejecting mechanism, said coin supporting means being adjustable and removable as a unit, said coin ejector ring having an extension for the support of coins in said coin tube after coins have been ejected from said coin support, said auxiliary base plate casting being provided with a horizontal slot to receive the coin supporting extension of the coin ejector ring, and being also provided with a horizontal slot to receive the lower end of the coin ejector trigger, and being provided also with integral pivot posts for the mechanism for operating the coin ejector ring.

75 In witness whereof, I hereunto subscribe my name this 30th day of December, A. D., 1925.

ROBERT H. SHARP.
